DESIGN FOR A DRESS

Maurice Extract, New York, N. Y.

Application December 18, 1936, Serial No. 66,611

Term of patent 3½ years

To all whom it may concern:

Be it known that I, Maurice Extract, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the skirt portion of my dress, which features a stitched upper portion consisting of in-

laid folds concealing the contrasting stripes, and an unstitched lower portion revealing the concealed contrasting stripes, giving same the appearance of shadow pleats in combination with the blouse portion of the dress, having the stripes on the front bodice portion conforming to the diagonal surplice effect "opening," which ends at the armhole, and said stripes being arranged to contrast to the balance of the blouse, which stripe formation is at right angles to the arrangement of the stripes on the skirt, as shown.

I claim:

The ornamental design for a dress, substantially as shown and described.

MAURICE EXTRACT.
